ATHLETIC SHOE

Robert B. Wolf, 9046 E. Washington Blvd., Pico Rivera, Calif.

Filed June 1, 1965, Ser. No. 85,539

Term of patent 14 years

(Cl. D7—5)

FIG. 1 is a side elevational view of an athletic shoe, showing my new design;

FIG. 2 is a bottom plan view of the same;

FIG. 3 is a vertical fragmentary longitudinal sectional view, as seen on line 3—3 of FIG. 2;

FIG. 4 is a transverse vertical sectional view, as seen on line 4—4 of FIG. 2; and

FIG. 5 is a transverse vertical sectional view, as seen on line 5—5 of FIG. 2.

The dominant features of my design reside in the portion shown in full lines.

I claim:

The ornamental design for an athletic shoe, as shown and described.
